UNITED STATES PATENT OFFICE.

LEVIN FAUST, OF ROCKPORT, ILLINOIS.

DESIGN FOR A HATCHET.

Application filed May 23, 1922. Serial No. 2,383. Term of patent 14 years.

To all whom it may concern:

Be it known that I, LEVIN FAUST, a citizen of the United States, residing at Rockford, in the county of Winnebago and State of Illinois, have invented a new, original, and ornamental Design for Hatchet, of which the following is a specification, reference being had to the accompanying drawing, forming a part thereof.

In the drawing:

Fig. 2 is a top view thereof.

I claim:

The ornamental design for a hatchet, as shown.

LEVIN FAUST.
